INKING MECHANISM FOR ROTARY IN-
TAGLIO PRINTING MACHINESRichard A. Krahmer, Yonkers, N. Y., assignor to
R. Hoe & Co., Inc., New York, N. Y., a corpo-
ration of New York

Application April 4, 1936, Serial No. 72,733

13 Claims. (Cl. 101—169)

This invention relates to doctor blade mechanism for printing machines and more particularly to a doctor blade wiping device for use with such mechanisms.

5 In rotary intaglio printing machines, a doctor blade is used to remove surplus ink from the surface of the printing cylinder. The blade is usually reciprocated lengthwise on the cylinder and as it reciprocates, ink adhering thereon is carried beyond and falls from the end of the doctor blade outside of the fountain where it must be caught and returned.

10 The principal object of the present invention is to provide a blade wiping device which will obviate the above disadvantage by removing the ink from the doctor blade and its holder before any ink adhering thereto reaches the end of the fountain.

15 Another object is to provide a doctor blade mechanism having included in its structure a wiping device adapted to engage and wipe a doctor blade as the same is reciprocated along a printing cylinder, and before the wiped portion of the blade passes the end of the fountain, without interfering with the efficient operation of the mechanism.

20 A further object of this invention is to provide a doctor blade wiping device for the above purpose, which is adapted to maintain a blade wiper in close wiping contact with the blade from a point closely adjacent the point of contact of the blade upon the cylinder and is resiliently held in such position whereby the blade will be free to move and be maintained in proper engagement 25 with the cylinder.

25 A still further object of this invention is to provide in a doctor blade wiping device a substantially universal movement permitting mounting for the wiper whereby it will adapt itself to 30 the form and position of the blade as it is pressed into contact therewith by suitably provided resilient means.

35 It is also an object of this invention to provide a doctor blade mechanism of generally improved construction, whereby the device will be simple, durable and inexpensive in construction, as well as convenient, practical, serviceable and efficient in its use.

40 With the foregoing and other objects in view which will appear as the description proceeds, the invention resides in the combination and arrangement of parts, and in the details of construction hereinafter described and claimed.

45 50 55 The preferred embodiment of the invention is

illustrated in the accompanying drawings, wherein:

Figure 1 is an end view of a part of a rotary intaglio printing machine having doctor blade wiping mechanism embodying the features of this 5 invention, certain elements thereof being shown in section indicated by the arrows 1—1 of Figure 2;

Figure 2 is a plan view partly broken away showing portions of the machine shown in Figure 1, 10 and looking in the direction indicated by the arrow 2;

Figure 3 is an enlarged sectional view of a portion of Figure 1, as seen in the direction of arrow 3 of Figure 2, to particularly show the wiping 15 device of this invention;

Figure 4 is an enlarged plan view of the wiping device shown in Figure 3; and

Figure 5 is an enlarged sectional view of the wiping device taken on line 5—5 of Figure 3. 20

The mechanism selected to illustrate the features of this invention, the pertinent parts of which are shown in Figures 1 and 2, includes an ink reservoir or fountain 11, in which a printing cylinder 12 rotates and is partially immersed in 25 the ink therein, and a doctor blade 13 clamped in a holder 14 which is held by arms 15 pivotally mounted in brackets 16. Suitable means is provided to maintain the doctor blade 13 in close engagement with the cylinder 12 to cause it to 30 remove surplus ink from the cylinder's surface, and is herein illustrated as a pair of cams 17 fastened to a shaft 17' rotatably supported in the brackets 16 and actuated by a handle 18, which is also secured to the shaft 17', the said 35 cams 17 being operatively engaged with the arms 15 to move same when desired, as will appear hereinafter.

The bracket 16 is mounted upon a table 19 and preferably the arrangement is such that it may be 40 adjusted transversely of the table toward and away from the cylinder by a hand wheel 21 through the use of a threaded spindle 22 in cooperation with internal threads provided in the base of the bracket 16. The table 19 is slidably 45 mounted for longitudinal movement relatively to the cylinder 12, upon a standard 23, being guided in its movements by cooperating ways 24. A crank disc 25 rotatable by means of a shaft 26, which is connected in a suitable manner to a 50 driven part of the machine is adapted to reciprocate the table 19 due to its connection therewith through a link 27. The reciprocation of the table 19 moves the doctor blade 13 longitudinally back and forth upon the cylinder 12. 55

By the use of the above described parts, excess ink is removed from the surface of the cylinder 12 leaving its etched portions suitably supplied with ink, whereby the impressions or design thereon will be printed upon a web 28 passing between the cylinder 12 and an impression cylinder 29. A suitable ink guard 31 extending lengthwise of the holder 36 is provided to prevent the surplus ink removed from the cylinder 12 from creeping up the holder and dropping over the adjacent edge 32 of the fountain 11. The ink guard 31 is herein illustrated as being a substantially flexible blade 33 extending from a bar 34 secured to the adjacent fountain edge 32 and overhanging it to direct any ink collected thereby back into the fountain.

In its back and forth travel longitudinally of the cylinder 12, each end of the doctor blade 13 passes beyond the end of the cylinder. Surplus ink adhering to the underside of the blade 13 is carried beyond and flows over the end of the cylinder and is thrown off by centrifugal force on the adjacent machine parts. To obviate this and other disadvantages incident to this action, the means herein disclosed is provided to wipe the ink from the doctor blade 13 as it is reciprocated and so as to prevent it from reaching the end of the cylinder.

The preferred form of the invention includes a doctor blade wiper 35, a holder 36 for the doctor wiper 35, and resilient means 37 to maintain the doctor wiper 35 in wiping contact with the blade 13. There is further provided an ink receiving tray 38 at each end of the cylinder to receive any surplus ink that may pass either of the wipers 35 should they fail to thoroughly wipe the blade 13 due to wear or other inadvertent causes. Each tray 38 is provided with a side wall 39 to which the wiper 35 and its holder is swingably and slidably mounted, another side wall 41, a back wall 42, and a bottom wall 43, herein shown having screws 44 passing therethrough and into a part of the fountain to secure the tray and wiper parts to the machine. The other end 45 of the tray is open and abutted against the bar 34 and a part 46 extending along the same. An opening 47 is provided in the wall 39 through which any ink received by the tray 38 may flow back into the ink fountain 11.

The holder 36 is preferably formed from sheet metal bent into a U-shape in cross section and the wiper 35 preferably made of rawhide or the like is disposed between the side arms thereof. A plate 48 is disposed against one side arm of the holder 36 and screws 49 and 51 are passed through the plate 48, the holder 36 and the wiper 35 and threaded into the tray side wall 39 to support the holder thereagainst. The screws 49 and 51 are shouldered screws whereby the holder 36 is snugly held against the wall 39 but not clamped thereto, being free to swing and to slide to dispose the wiper 35 into proper engagement with the doctor blade 12 under the urge of the leaf spring 37 which is secured to the side wall 39 by screws 53 and has its springable free end 52 in engagement with the base 55 of the holder 36.

To permit the swinging and sliding of the holder 36 with the wiper 35 they are each provided with an elongated opening 56 whose long axis is substantially parallel to the base 55 of the holder 36 and through which the screw 49 extends. The opening 56 permits swinging of the holder 36 and wiper 35 toward and away from the blade 13 about the screw 49 as a pivot and also permits sliding of these parts to and from

the cylinder. An enlarged opening 57 is provided in the wiper 35 and holder 36 which has its long axis at an angle to the base 55, the angle being such that one of the long sides 58 of the opening 57 is engaged by the screw 51 and acts therewith to cam the angularly formed blade engaging surface 59 of the wiper 35 into close contact with the undersurface of the doctor blade 13 and its point 61 substantially at the edge of the blade in contact with a bridge piece 50 secured to an overhanging ink guard 60, which in turn is attached to means forming a part of each of the pair of ink fountain packing caps 50' shown diagrammatically in dotted lines in Figure 1. It is to be understood that a bridge piece 50 and an ink guard member 60 is employed at each end of the cylinder 12. Each of the bridge pieces 50, the undersurface of which contacts the periphery of the cylinder 12, is particularly adapted to support the doctor blade across the gap beyond the adjacent end of the cylinder. The ink guards 60 are designed and adapted to prevent ink thrown from the end of the cylinder while rotating, from reaching the outside of the machine. The resilient member or spring 37 by contact with the base 55 of the holder 36 constantly urges the wiper 35 into contact with the blade 13 along its undersurface, and due to the arrangement of the openings 56 and 57 and the cooperation therewith of the screws 49 and 51 respectively, the urging action of the spring end 52 directs the wiper 35 upwardly and forwardly into such position.

By the provision of one of the above described doctor wipers adjacent to each end of the cylinder 12, the reciprocating doctor blade 13 is wiped and the surplus ink thereon collected from the cylinder 12 is removed before it reaches the cylinder end. The removed ink is thus prevented from running over the cylinder end and being thrown or dropping therefrom on adjacent machine parts. The flexible nature of the mounting for the wiper whereby it may be termed a longitudinally floatable member, insures provision for movements inherent in the use of a flexible doctor blade 13 and compensates for irregularities on the surface of the cylinder 12.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the mechanism herein disclosed forms a part of the invention included in this application.

What I claim is:

1. In a rotary intaglio printing machine, a flexible doctor blade adapted to reciprocate longitudinally along and in contact with the peripheral surface of a printing cylinder, a blade wiper mounted for free movements toward the blade and transversely to the direction of movement of the blade to engage the surface of said blade, and means to resiliently press said wiper against said blade.

2. In a rotary intaglio printing machine, a doctor blade adapted to reciprocate longitudinally along and in contact with the peripheral surface of a printing cylinder, blade wiping means at each end of the cylinder to engage said blade along its surface from a point closely adjacent a point of contact of the blade on the cylinder, and means to urge said wiping means

substantially simultaneously upwardly against said blade and forwardly toward the point of its contact with the cylinder.

3. In a rotary intaglio printing machine, a doctor blade adapted to reciprocate longitudinally along and in contact with the peripheral surface of a printing cylinder, blade wiping means at each end of the cylinder to engage said blade along its undersurface from a point closely

10 adjacent its point of contact with the cylinder, means to urge said wiping means against said blade, and means to cam said wiping means upwardly and forwardly when urged against said blade.

15 4. In a rotary intaglio printing machine, a doctor blade adapted to reciprocate longitudinally along and in contact with the peripheral surface of a printing cylinder, blade wiping means to engage the undersurface of said blade 20 including a part having a surface extending across said blade and terminating in a point, said part being mounted for swinging and sliding movement toward and across said blade to present said surface against said blade and said 25 point adjacent the edge of said blade in contact with the cylinder.

5. In a rotary intaglio printing machine, a doctor blade adapted to reciprocate longitudinally along and in contact with the peripheral 30 surface of a printing cylinder, blade wiping means to engage the undersurface of said blade including a part having a surface extending across said blade and terminating in a point, said part being mounted for swinging and sliding 35 movement toward and across said blade to present said surface against said blade and said point adjacent the edge of said blade in contact with the cylinder, and means to constantly urge said blade wiping means into substantially close 40 contact with said blade.

6. In a rotary intaglio printing machine, a doctor blade wiping device, a blade engaging wiper part having elongated openings therein, means passing through said openings to secure 45 said part to a stationary member, one of these openings in said part being disposed with its long axis at an angle to the other, and means tending to swing said part upwardly about one of said securing means whereby the other of said 50 securing means will cooperate with a wall of the angularly disposed opening to slide said part forwardly.

7. In a rotary intaglio printing machine, a flexible doctor blade, means to reciprocate said doctor blade along the surface of a printing cylinder, wipers mounted for free movements toward the undersurface of the blade and transversely to the direction of movement of said blade to engage the same adjacent its points of contact with the cylinder to wipe the blade as it is reciprocated, and springs to maintain the wipers in such engagement.

8. In a rotary intaglio printing machine, a

flexible doctor blade, means to reciprocate said doctor blade along the surface of a printing cylinder, a blade wiper mounted for movements toward the blade and transversely to the direction of movement of said blade to engage the undersurface of said blade adjacent its points of contact with the cylinder to wipe the blade as it is reciprocated, and means to constantly urge said wiper into its movable positions.

9. In a rotary intaglio printing machine, a doctor blade, means to reciprocate said doctor blade along the surface of a printing cylinder, means engaging the undersurface of said blade adjacent its point of contact with the cylinder to wipe the same as it is reciprocated, and means 10 to urge said blade wiping means upwardly against said blade and forwardly toward the point of contact of said blade with the cylinder.

10. In a rotary intaglio printing machine, a doctor blade wiper, a wiper part adapted to engage the undersurface of a doctor blade, a spring adapted to urge said part into such engagement, and means to secure said part to a stationary member including means to cam said part forwardly when it is urged against said blade by 25 said spring.

11. In a rotary intaglio printing machine, a doctor blade wiper, a wiper part adapted to engage the undersurface of a doctor blade, a spring adapted to urge said part into engagement, 30 means passing through an opening in said part to secure it to a stationary member, the opening in said part being elongated and having its long axis disposed at an angle, said securing means cooperating with the angularly disposed walls of 35 the opening in said part to cam said part forwardly when it is urged against said blade by said spring.

12. In a rotary intaglio printing machine, a printing cylinder, an ink reservoir in which said cylinder rotates, a flexible doctor blade in engagement with said cylinder, means to reciprocate said doctor blade along said cylinder lengthwise thereof, a member freely movable into engagement with the undersurface of said doctor 40 blade adjacent its point of contact with said cylinder whereby it will follow the blade during movement thereof, and resilient means to press said member against said blade, whereby said blade is wiped by said member as it is reciprocated.

13. In a rotary intaglio printing machine, a printing cylinder, an ink reservoir in which said cylinder rotates, a doctor blade in engagement with said cylinder, means to reciprocate said doctor blade along said cylinder lengthwise thereof, a member in engagement with the undersurface of said doctor blade adjacent its point of contact with said cylinder, and means to press said member upwardly against said blade and forwardly toward the point of contact of said blade with said cylinder.

RICHARD A. KRAHMER.
